CIGARETTE HOLDER

Samuel Wolf, Brooklyn, N. Y.

Application February 13, 1953, Serial No. 23,597

Term of patent 3½ years

(Cl. D85—8)

To all whom it may concern:

Be it known that I, Samuel Wolf, a citizen of Roumania, residing at Brooklyn, in the county of Kings and State of New York, have invented a new, original, and ornamental Design for a Cigarette Holder, of which the following is a specification, reference being had to the accompanying drawing forming a part thereof.

In the drawing:

I claim:

The ornamental design for a cigarette holder, as shown.

SAMUEL WOLF.
